VISE

Clarence G. Garrigus, Haddam, and Cedric B. Cross, Moodus, Conn., assignors to Production Devices Incorporated, East Hartford, Conn., a Corporation of Connecticut

Application October 26, 1940, Serial No. 362,957

4 Claims. (Cl. 81—17)

One object of the invention is to provide a powerful quick acting machine tool vise.

Another object of the invention is to economize on the amount of compressed air used to furnish the required amount of power in the vise.

Another object of the invention is to provide means for quickly and easily releasing the power in the vise leaving the jaws in position to receive and hold new work ready for operation.

A further object of the invention is to provide a powerful vise easily adaptable for any work about to be machined.

To these ends and also to improve generally on devices of the class specified is the object of the invention hereinafter described and claimed.

Fig. 1 is a plan view of vise;

Fig. 2 is a lateral view of the same partially cut away approximately along line 2—2 of Fig. 1 and viewed in the direction of the arrows;

Fig. 3 is a transverse vertical section taken along line 3—3 of Fig. 2 and viewed in the direction of the arrows; and

Fig. 4 is a transverse vertical section taken along line 4—4 of Fig. 2 viewed in the direction of the arrows.

Referring to the drawings, a base 10 has mounted thereon a stationary jaw 11 and a movable jaw 12.

The stationary jaw 11 is adjustable to a predetermined fixed position by means of a bolt 13, slots as at 31 in the base 10, and keys 32 adapted to fit in the predetermined slots. The bolt 13 holds the jaw 11 secure in the desired stationary position. The position of the stationary jaw, of course, depends on the size of the material to be worked while held by the jaws and said material is hereinafter referred to as the work.

The power that we prefer to use to operate the movable jaw 12 is compressed air. Vises operated by compressed air are not new and the difficulty with them has been that they do not hold the work securely enough to operate on the work with speed and with sufficient cut in the work to be satisfactory for fast production. In our vise compressed air, controlled by valves not shown but well known in the art, enters the chamber 14 and forces the air piston 15 upward. Rollers 16 suitably collared ride horizontally in suitable slots 15a in said piston 15 and engage respectively the cams 17 and 18 and carry both cams also upwardly. The cams 17 and 18 have opposing convex cam surfaces 17a, 18a which it will be seen are in rolling engagement with each other.

The cam 18 has a fixed pivotal point as at 19 secured by pin 20 to the arms 10a integral with the base 10.

The cam 17 is pivotally secured by the pin 21 to the movable jaw 12. Thus, upon upward movement of the piston 15, because of the rolling engagement of cam surface 17a with cam surface 18a, said cam 17 serves to move said movable jaw 12 toward said stationary jaw 11.

10 It will be seen that the pivotal point of the cam at 21 is not fixed but moves horizontally with the movable jaw. It will also be noted that the contact between the engaging surfaces of the cams 17 and 18 as at 22 is, because of the 15 rolling engagement between said opposing convex cam surfaces, always below or out of alignment with the pivotal points of the cams at 21 and at 19.

The movable jaw 12 rides as at 23 on the base 20 10 and is held slidably in place by a plate 24 secured by bolts 25.

A coil spring 26 engages a stud 27 in the jaw 12 and a lug 28 in the base 10 so that the tension therefrom holds the cams 17 and 18 constantly 25 in contact as at 22.

The coil springs 29 engage the base of the piston and are put under compression as the compressed air forces the piston 15 upward, so that when the air pressure is released the springs 29 30 force the piston, the cams and hence, the movable jaw 12 to its open or normal position as shown in Fig. 2.

The convex engaging contact surfaces of the 35 respective cams as at 22 are not true arcs, but rather the portions of the surfaces 17a, 18a in initial contact are slightly cut away so that the respective arcs are steeper initially thus causing faster movement of the movable jaw 12 before it meets up with the work so as to save time in 40 operation.

Speed in operation is important both before the movable jaw meets the work and at the time of releasing. For instance if the pressure is 45 variably increasing up to the time to release a wedging is caused which will delay releasing. It will be noted that the contact point 22 practically does not move so that the predetermined pressure at the jaw is constant and no wedging is caused to delay the release.

50 We claim:

1. In a device of the character described, a stationary jaw, a movable jaw and means for moving said movable jaw toward and away from said stationary jaw comprising a reciprocally 55 movable piston, a member supported from a fixed

pivot and having a convex cam surface, a second member supported from a pivot movable with and carried by said movable jaw and having a convex cam surface engageable with said first-named cam surface, means for coupling both said members to said reciprocally movable piston to rotate them about their respective pivots upon reciprocation of said piston, and means for maintaining said cam surfaces in rolling contact during said reciprocation of said piston whereby the contact between said surfaces during operation always remains substantially in a single horizontal plane below the level of said pivots.

2. In a device of the character described, a stationary jaw, a movable jaw and means for moving said movable jaw toward and away from said stationary jaw to effect clamping pressure on and release of work pieces between said jaws, said means comprising a pair of members having opposing convex cam surfaces adapted to engage each other with rolling contact, fixed pivot means for supporting one of said members, pivot means movable with and carried by said movable jaw for supporting the other of said members, a reciprocally movable element, means for coupling said element with said two members to rotate the latter about their respective pivot means upon reciprocation of said element whereby the contact between said cam surfaces during reciprocation of said element always remains substantially in a single horizontal plane below the level of said pivot means.

3. In a vise of the character described, a stationary jaw, a movable jaw, and means for moving said movable jaw, comprising a pair of members having opposing convex cam surfaces adapted to engage each other with rolling contact, fixed pivot means for supporting one of said members, pivot means movable with said movable jaw for supporting the other of said members, a reciprocally-movable pressure-actuated element,

roller means coupling said element with each of said members to rotate the latter about their respective pivot means upon reciprocation of said element, spring-actuated means for maintaining contact between said convex cam surfaces, and spring-actuated means for urging said reciprocally-movable element in one direction of its reciprocal motion, both said pivot means being so positioned that the contact between said convex cam surfaces during reciprocation of said element always remains substantially in a single horizontal plane below the level of both said pivot means.

4. A vise comprising a base, an adjustable stationary jaw, a movable jaw slidably supported with respect to said base and movable toward and away from said first-named jaw, means tending to maintain said jaws apart, and means for moving said movable jaw toward said stationary jaw, said last-named means including a pair of members having opposing convex cam surfaces adapted to engage each other with rolling contact, fixed pivoted means carried by said base for rotatably supporting one of said members, pivot means movable with said movable jaw for supporting the other of said members, a reciprocally-movable, pressure-actuated piston, roller means coupling said piston and each of said members to rotate the latter about their respective pivots upon reciprocation of said pressure-actuated piston, both said pivot means being positioned so that the contact between said cam surfaces during reciprocation of said piston always remains substantially in a single horizontal plane below the level of said pivot means, and the said convex cam surfaces being arcs whose initial portions are so cut away as to provide faster movement of said movable jaw during a portion of its motion toward said movable jaw.
